No. 37,116.

Patented August 30, 1904.

UNITED STATES PATENT OFFICE.

EMANUEL B. ADLER, OF PITTSBURG, PENNSYLVANIA, ASSIGNOR TO H. ADLER COMPANY, OF PITTSBURG, PENNSYLVANIA, A CORPORATION OF PENNSYLVANIA.

DESIGN FOR A HEATING-STOVE TOP.

SPECIFICATION forming part of Design No. 37,116, dated August 30, 1904.

Application filed July 2, 1904. Serial No. 215,183. Term of patent 7 years.

To all whom it may concern:

Be it known that I, EMANUEL B. ADLER, a citizen of the United States, and a resident of the city of Pittsburg, county of Allegheny, and 5 State of Pennsylvania, have invented a new, original, and ornamental Design for Heating-Stove Tops.

The figure is a perspective view of the heating-stove top.

What I claim is—

The ornamental design for a heating-stove top, substantially as shown.

EMANUEL B. ADLER.
